UNITED STATES PATENT OFFICE.

WILLIAM F. MORSE, OF NEW YORK, N. Y.

GARBAGE-FURNACE.

No. 836,830.

Specification of Letters Patent.

Patented Nov. 20, 1906.

Application filed August 3, 1905. Serial No. 272,464.

To all whom it may concern:

Be it known that I, WILLIAM F. MORSE, a citizen of the United States, residing at New York, in the county of New York and State of New York, have invented certain new and useful Improvements in Garbage-Furnaces, of which the following is a specification.

My invention relates to furnaces designed for the burning of garbage; and its novelty consists in the construction and adaptation of the parts, as will be more fully hereinafter pointed out.

In the drawings, Figure 1 is a longitudinal vertical section of a furnace embodying my invention, and Fig. 2 is a vertical transverse section of the same on the plane of the line 2-2 in Fig. 1.

In the drawings, 1 is the primary combustion-chamber or oven, provided with end walls 2 and 20, side walls 3 and 30, and a roof 4, which has a door 5, through which the garbage is fed. It also has a primary grate 6 and a sloping receiving-platform 7, provided with suitable vertically-placed openings or perforations 8.

Arranged at the bottom of the furnace is the gas-expanding chamber 9, the bottom of which is the floor 10 of the furnace and intermediate which and the platform 7 is placed a sloping curtain or platform 11, so that between this curtain and the platform there is formed a flue 12.

Between the grate 6 and the platform 7 and reaching down to the floor 10 is a partition 13, separating the fire-box or ash-pit 14 from the interior of the furnace. The curtain 11, while it is secured to and supported from the end wall 20, does not extend quite to the partition 13, there being a chamber 15 formed between the lower terminus 111 of the partition, the floor 10, and the platform 7.

Adjacent to the wall 20 is arranged the chimney 16, enlarged somewhat at the bottom, where it is provided with a grate 17 and a plurality of transverse arched partitions 18 18 of fire-brick above the same. These partitions are perforated, as at 180 180, to permit of the free passage of the gases, as herein-after described. The chimney is provided with a door 19 to admit of access to the grate 17.

Beneath the floor 10 there are arranged a plurality of air-conduits 40 40. These extend from the outer air, where they are provided with valve-controlled inlets along the bottom of the furnace and thence up through the wall 13 or in any other convenient man-

ner, so that they may discharge their heated contents beneath the grate 6.

Suitable openings, as 21, extend from the expanding-chamber 9 to the space above the grate 17.

It will of course be understood without any further explanation that the usual adjuncts of dampers, stoke-holes, and the like are provided and that the parts are made of suitable materials, such as steel or fire-brick, in the manner customary with engineers and other persons skilled in the art.

The mode of operating the apparatus is as follows: A fire is first built upon the grate 17, any ordinary fuel being employed. This is for the purpose of establishing a current of air through the apparatus and heating the partitions 18 18. A fire is then lighted upon the grate 6. This heats the air in the primary combustion-chamber and heats the inclined platform 7. After these two fires have been well started the door 5 is opened and the garbage to be treated is thrown down upon the platform 7. It is there first dried and then burned. If the quantity is great, the garbage is continually stoked downward toward the grate 6, and a portion of it serves as additional fuel to assist in the operations of the apparatus. Portions of the garbage also fall down through the apertures 8 8 into the flue 12 and chamber 15, where they are speedily destroyed. The products and partial products of combustion pass upward along the sloping platform 7, the direction of their movement being assisted by its position. They then pass around its uppermost end and downward through the flue 12, formed between it and the curtain 11, into the chamber 15. They then pass into the expanding-chamber 9. Here they expand and the reactions which have been taking place down to this time cease or almost cease. They then pass out at the upper end of the chamber 9 into the chimney above the grate 17. The fresh fire on this grate causes the immediate ignition of all of the gases capable of such a reaction and they pass upward through the holes 180 180 in the partitions 18 18 and leave the throat of the chimney practically consumed and innocuous.

The inclination of the platform 7 upward away from the grate constantly decreases the area of the combustion-chamber, and thereby causes a more intimate contact of the products of combustion with the garbage on the platform, such inclination also facilitating

the downward movement of portions of the superposed garbage to the grate to form additional fuel thereon.

The downward incline of the curtain 11 5 greatly facilitates the passage with the products of combustion of the very light, dried, and burned particles deposited on the apron both through the apertures of the platform and around the upper end thereof. The position of the apron and platform also forms an inclined flue, through which the products of combustion pass downward, and owing to their superior lightness the lightly-heated gases are caused by such inclination of the 15 flue to more closely contact with the under side of the platform, keeping it hot and greatly facilitating the initial incineration of the garbage on the platform.

The platform 7, the curtain 11, and the partitions 18 18, together with the walls of the furnace, soon become very hot and by their radiation assist materially in maintaining the continuity of the operation of the apparatus.

In order further to utilize the heat, I place 25 the air-conduits 40 40 beneath the furnace-floor. As soon as the furnace is fairly under way the air is let into the inlet-valve, becomes heated in its passage under the floor 10, and finally emerges beneath the grate 6 30 sufficiently heated materially to increase the economy of the operation of the furnace.

What I claim as new is—

1. A garbage-crematory comprising a combustion-chamber and grate and a perforated 35 inclined receiving-platform, leading upward from the grate, an expanding-chamber arranged beneath the combustion-chamber the upper wall of which consists of a downwardly-inclined deflecting-curtain below the platform forming a flue between the platform and curtain, and a chimney connected with the expanding-chamber.

2. A garbage-furnace comprising a lower 45 expanding-chamber provided with an upper wall inclined toward the outlet thereof, an upper combustion-chamber provided with a perforated floor below and inclined in a direction substantially parallel to the upper wall of the expanding-chamber forming a flue between the floor of the combustion-chamber and the upper wall of the expanding-chamber, and a fire-grate in the combustion-chamber at the lower end of the floor 50 thereof.

55 3. A garbage-furnace comprising a lower expanding-chamber provided with an upper wall inclined toward the outlet thereof, an

upper combustion-chamber provided with a floor inclined in a direction substantially parallel to the upper wall of the expanding-chamber forming a flue between the floor of the combustion-chamber and the upper wall of the expanding-chamber and a fire-grate in the combustion-chamber at the lower end of the floor 60 thereof in combination with a chimney, connected with the outlet of the expanding-chamber, and provided with a fire-grate at or near its bottom.

4. A garbage-furnace comprising a lower 70 expanding-chamber provided with an upper impervious wall inclined toward the outlet thereof, an upper combustion-chamber provided with an apertured floor inclined in a direction substantially parallel to the upper wall of the expanding-chamber forming a 75 flue between the floor of the combustion-chamber and the upper wall of the expanding-chamber and a fire-grate in the combustion-chamber at the lower end of the floor thereof.

5. A garbage-crematory comprising a combustion-chamber and grate, an inclined receiving-platform, leading upward from the grate, an expanding-chamber arranged beneath the combustion-chamber, and the 85 upper wall of which consists of a downwardly-inclined deflecting-curtain forming a flue between the platform and curtain and an air-conduit beneath the furnace to receive the radiated heat therefrom and leading from the 90 outer air to the space beneath the grate of the combustion-chamber.

6. A garbage-furnace comprising a lower 95 expanding-chamber provided with an upper wall inclined toward the outlet thereof, an upper combustion-chamber provided with a floor inclined in a direction substantially parallel to the upper wall of the expanding-chamber forming a flue between the floor of the combustion-chamber and the upper wall 100 of the expanding-chamber and a fire-grate in the combustion-chamber at the lower end of the floor thereof, in combination with a chimney connected with the outlet of the expanding-chamber and provided with a fire-grate at or near its bottom and transverse 105 partitions above the fire-grate.

In testimony whereof I affix my signature in presence of two witnesses.

WILLIAM F. MORSE.
